Primary Examiner — Samantha Q Lawrence(74) *Attorney, Agent, or Firm* — Morgan, Lewis & Bockius LLP**CLAIM**

The ornamental design for a surgical tool cutting bit as shown and described.

DESCRIPTION

FIG. 1 is a perspective view of a surgical tool cutting bit showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 6 Drawing Sheets---
